JOSEPH G. WORKER, OF EAU CLAIRE, WISCONSIN.

STOKING MECHANISM.

Application filed October 30, 1920. Serial No. 420,663.

To all whom it may concern:

Be it known that I, JOSEPH G. WORKER, a citizen of the United States, and a resident of Eau Claire, in the county of Eau Claire and State of Wisconsin, have invented 5 a new and useful Improvement in Stoking Mechanism, of which the following is a specification.

This invention relates to stokers and particularly to that class of stokers known as 10 automatic stokers commonly used in heating steam boilers. Such stokers usually comprise an inclined combustion grate supplied with fuel at the front end either by over- 15 feed or underfeed mechanism or both, the combustion grate being usually supplemented by a pivoted dump grate closing the dumping opening at the lower and rear end of the grate between the lower end of the 20 combustion grate and the customary bridge wall of the furnace.

In the usual type of furnace the mixture of ashes and slag accumulating over the dump grate adheres firmly to the bridge 25 wall. This accumulation interferes with the proper operation of the dump grate and the combustion of the fuel at the rear of the furnace and must therefore be dislodged at quite frequent intervals. The slag adheres 30 firmly and occasions much difficulty in its removal, necessitating severe manipulation with a heavy iron rod or paddle. The frequency and severity of the operation does appreciable damage to the bridge wall necessitating 35 expensive repairs thereof which occasion costly delays in the operation of the plant.

The principal objects of this invention are the production of a stoking mechanism 40 in which the accumulation of slag adjacent the bridge wall is substantially prevented; the production of a stoking mechanism wherein the fuel usually wasted at the rear end of the furnace is burned; the production 45 of a stoking mechanism wherein the fuel is properly manipulated automatically so as to cause complete combustion of the fuel with a minimum production of slag; the production of an automatic stoking mechanism 50 that requires comparatively little manual labor in keeping the ash discharge open and free from slag accumulation; the production of an improved dump grate mechanism whereby combustion is facilitated at 55 the rear of the furnace; the production of an improved dump grāte which is substan-

tially self-cleaning and therefore practically free of slag deposits; the production of means in connection with a dump grate for preventing burning of the grate, and such other objects as may hereinafter appear. Certain embodiments of the invention are illustrated in the accompanying drawings wherein—

Fig. 1 is a partial plan view in part dia- 60 grammatic of the rear end of a furnace showing the improved dump grate mechanism with portions shown in horizontal section;

Fig. 2 is a vertical section in part dia- 65 grammatic through a furnace on line II—II of Fig. 1;

Fig. 3 is an enlarged vertical section showing grate operating mechanism; and

Fig. 4 is an end view of a valve used in 70 connection with the cylindrical dump grate.

This invention relates particularly to dump 75 grate mechanism used in connection with a well known type of underfeed automatic stoker. Such a stoking mechanism is illus- 80 trated in Fig. 2, wherein the fuel is fed into a hopper 1 and is passed into a furnace through a passage 2 by means of a reciprocating plunger 3 operated by a motor 4 which continuously rotates a shaft 5 and with it a 85 crank 6. The plunger 3 is connected to the crank 6 by means of a link 7 which reciprocates the plunger back and forth at each revolution of the shaft 5.

After passing through the passage 2, the 90 fuel enters a number of fuel troughs 8 arranged in parallel relation with tuyère boxes 9 between them. The coal is therefore fed from beneath the burning surface, and air is supplied to the fuel bed through the 95 openings in the tuyère boxes communicating with a wind box 10 arranged beneath the grate construction. The wind box 10 is supplied with a blast of air through a pair of vertically disposed conduits 10a (Figs. 1 and 100 2). The grate mechanism just described is usually supplemented by a moving grate 11 which, in some furnace constructions, is adapted to be reciprocated from and toward the tuyère boxes by any suitable 105 mechanism operated by the motor shaft 5. The air supplied to the grates just described is controlled by butterfly valves 12 arranged in various places in the wind box 10.

At the rear end of the furnace, a bridge 110 wall 13 is separated from the rear end of the

moving grate 11 so as to provide a refuse pit or dumping opening 14 between the moving grate and the bridge wall through which ashes and other residue from the fuel may be discharged. In the refuse pit 14, a plurality of cylindrical dump grates 15 are disposed longitudinally thereof and are preferably situated beneath and at the rear of the rearmost active grate 11 so as to receive the material discharged therefrom. These cylindrical grates are closed at their ends and are pivoted for rotation upon a hollow trunnion shaft 16 extending entirely across the width of the furnace or transverse to the direction of flow of the fuel. The trunnion shaft 16 is mounted in hollow bearings 17 and is provided with two sets of perforations 18 and 19, the former being disposed so as to discharge into the interior of the cylindrical grates 15, and the latter perforations are adapted to communicate with chambers 20 in the hollow bearings 17 so that air supplied to the bearing chamber 20 through the pipe 21 may enter the interior of the trunnion and discharge through the openings 18 or from the other end of the trunnion into the chamber 20 and out through the conduit 22. The purpose of such circulation of air through the trunnion shaft will hereinafter appear.

The cylindrical dump grates 15 are hollow, the cylindrical shells thereof being provided with ports or perforations 23 through which air supplied to the interior of the dump grates may be discharged into contact with the material supported upon the cylindrical dump grates 15. It is the object of these perforations to supply a blast of air to the ash deposited on the upper surface of the dump grate. In order to economize the air and supply it only to that portion of the surface of the cylinder in contact with the ash, the interior of the cylindrical dump grate is provided with a segmental cylindrical valve 24 carried upon the trunnion shaft 16 by means of bearings or webs 25 integral with or secured to the valve 24. An end view of this valve is illustrated in Fig. 4 which shows that the cylindrical portion thereof extends through an arc of more than 180° and as shown in Fig. 2 prevents the escape of air through any perforations 23 except those between the points *a* and *b* which are uncovered by the valve. It will be seen that if the valve 24 is held stationary and the dump grate 15 rotated, the ports 23 located around the perforations of the dump grate will be successively opened at the point *a* and closed at the point *b* so that air only escapes through the points of the cylinder in contact with the mixture of fuel and ashes. By reason of the blast of air which may pass through the perforations any combustible material remaining in the ashes will be consumed.

The trunnion shaft 16 is supported upon rocker arms 27 which are keyed to a shaft 28 extending parallel with the dump grate, this shaft being mounted for rotation in suitable bearings 29 carried upon I-beams 30 which beams serve to support the rear end of the furnace structure. The shaft 28 is adapted to be rocked or oscillated by means of a worm gear segment 31 which is meshed with a worm 32 leading to the front end of the furnace where it is provided with a hand wheel (not shown) whereby the worm 32 may be manipulated. When it is desired to dump the grate, the worm 32 is actuated so as to move the worm gear 31 counterclockwise, which action will lower the trunnion shaft 16 and with it the dump grate so as to dump the furnace whenever it is desired. It will be seen that by this mechanism the relative position of the dump grate with respect to the moving grate 11 can be adjusted to suit operating conditions.

The dump grate 15 is adapted to be progressively rotated either continuously or intermittently, and where it is desirable to rotate the dump grate intermittently, the dump grates are provided with ratchet wheels 33 secured thereto in any suitable manner and cooperating with pawls 34 (Figs. 1 and 3) which are pivoted upon rocking levers 35 pivoted at their upper ends to the trunnion shaft 16 for oscillation thereabout. The lower end of each rocking lever 35 is pivoted to a connecting link 36 which extends forwardly of the furnace and is pivotally connected to a bell crank lever 37 pivotally carried by a bracket 38 secured to the I-beam 39 supporting the front end of the furnace. The forward arm of the rocking lever 37 is pivotally connected to a yielding link connection 40 which is pivoted at its upper end to the crank 6, operated by the motor 4. The yielding connection 40 may be of any suitable construction and as shown consists of telescoping members 44 and 45 and a spring 46 subject to compression upon the imposition thereon of a load greater than a predetermined safe load. The link 36 is supported between the bell crank 37 and the rocking lever 35 by means of a link 41. It will be seen from the foregoing that, for each revolution of the crank 6, the rocking lever 35 will be oscillated back and forth once and with each oscillation the weighted pawl 34 will ratchet over certain teeth of the ratchet wheel 33 so that for each oscillation of the lever 35 the cylindrical dump grate 15 will be intermittently rotated counterclockwise.

The rotation of the dump grate intermittently toward the bridge wall causes the ash to be agitated and moved toward the bridge wall and finally discharged into the ash pit beneath the dumping grate. Any clinkers too large to normally pass over the dump

15 and between the bridge wall will be crushed between such elements and discharged. The intermittent rotation of the dump grate also tends to prevent the formation of any large clinkers or the accumulation of slag and ashes adjacent the bridge wall, and therefore it will not be necessary to break up any such accumulations, except possibly once in twenty-four hours, or when 10 the furnace is given a general cleaning.

The air conduit 21 is connected with the conduit 10a and receives air therefrom which is passed through the trunnion shaft 16 and subsequently through the cylindrical grates 15. Any excess of air is returned to the wind box 10 through the conduits 22, previously referred to. This circulation of air prevents any overheating of the trunnion shaft and the cylindrical dump grate 15 and 20 therefore the dump grates are not liable to be burned out.

The trunnion shaft 16 is preferably rotatable in bearings 17, and the bearings 25 of the valves 24 preferably have loose fitting 25 collars 42 embracing the trunnion shaft 16. It is also desirable to provide the valves 24 with counterweights 43 (Fig. 4) so that they may be held by gravity in the position illustrated in Figs. 2 and 3.

30 While I have shown my invention in two forms, it will be obvious to those skilled in the art that it is not so limited, but is susceptible of various other changes and modifications without departing from the spirit thereof, and I desire, therefore, that only such limitation shall be placed thereupon as are imposed by the prior art or as are specifically set forth in the appended claims.

What I claim is:—

40 1. A dump grate for stoking mechanism comprising a moving hollow grate member provided with ports for the passage of fluid through the member into contact with the material on the surface thereof, and a valve 45 closing such ports as do not discharge into contact with said material.

2. A dump grate for stoking mechanism comprising a moving hollow grate member having a single chamber provided with 50 ports extending through the shell of the member exposed to contact with combustible materials and communicating with the interior of the grate member, means for supplying fluid to the interior of the grate member, and means closing such ports as 55 do not discharge into contact with said material.

3. The combination with a stoking mechanism of a combustion grate, a refuse pit at 60 the rear of the combustion grate, a moving hollow dump grate adjacent to the combustion grate and adapted to receive and to convey material discharged from the combustion grate, said hollow dump grate having 65 ports for delivering fluid to the material

supported thereon, means for intermittently moving the dump grate, and means closing such ports as do not discharge into contact with the material during the movement of the dump grate. 70

4. The combination with a stoking mechanism having a combustion grate terminating adjacent a dumping opening, of a rotary dump grate in said opening adjacent to said combustion grate, means for actuating said 75 dump grate for effecting an intermittent movement of the ash-supporting surface contiguous to the plane of the combustion grate, and means for bodily moving the dump grate substantially transversely to the 80 plane of the combustion grate.

5. A stoking mechanism comprising in combination, a combustion grate, a stop member spaced from the discharge end of the combustion grate to form a dumping 85 opening, a cylindrical dump grate in the opening, means for rotating the dumping grate so as to convey material from the combustion grate and crush it downwardly between the stop member and the dumping 90 grate, and means for bodily swinging said cylindrical dumping grate downwardly out of the path of the material passing through the dumping opening.

6. A stoking mechanism comprising in 95 combination, a combustion grate, a stop member spaced from the discharge end of the grate to form a dumping opening, a cylindrical dump grate in said opening adjacent to the combustion grate, spaced from the stop member and adapted to receive ash discharged from the combustion grate, means for rotating the dumping grate to move ash toward said stop member, and means for bodily adjusting the position of 100 the dump grate with respect to the stop member.

7. A dump grate for a stoking mechanism comprising a rotary hollow cylinder, means for supplying fluid to the interior of the cylinder, the shell of the cylinder having 110 ports for the discharge of fluid therethrough, and a valve for closing certain of said ports, so as to secure uniform directional discharge through the open ports during the rotation of the hollow cylinder. 115

8. A dump grate for stoking mechanism comprising a rotary hollow cylinder, means for supplying fluid to the interior of the cylinder, the shell of the cylinder having ports for the discharge of fluid in the cylinder through the grate surface thereof, and valve means closing each of the ports during a predetermined arcuate travel of the rotating cylinder. 120

9. Stoking mechanism comprising in combination, a combustion grate, means for feeding fuel to the grate, means for operating the fuel feeding means, a hollow rotary dump grate cooperating with the combus- 125

tion grate, means for rotating the dump grate actuated by the said operating means, said hollow dump grate having ports for the delivery of fluid to the material passing 5 thereover, and means closing the ports in that portion of the rotary grate which in its rotation is not supporting combustible material.

10. Stoking mechanism comprising in combination, a combustion grate, a wind box for supplying air to the grate, an air supply passage leading to the wind box, a hollow dump grate cooperating with the combustion grate, the shell of the dump grate 15 having air delivery ports, means for supplying air to the interior of the dump grate from the said air supply passage, and means for discharging air from the dump grate into the said wind box.

20. 11. Stoking mechanism comprising in combination, a combustion grate, a wind box for supplying air to the grate, an air supply passage leading to the wind box, a hollow dump grate cooperating with the combustion 25 grate, means connecting the interior of the dump grate with the said air supply passage and means connecting the interior of the dump grate with the wind box whereby air may pass from the supply passage 30 through the dump grate and into the said wind box.

12. Stoker mechanism comprising in

combination a combustion grate discharging into a refuse pit, a stop member spaced from the discharge end of the combustion grate 35 so as to provide a dump opening into the refuse pit, a rotary dump grate at one side of the refuse pit, a pivotal support for the dump grate at the said one side of the pit, and means for oscillating the dump grate 40 about the pivotal support.

13. A dump grate for fuel stoking mechanism, comprising a hollow perforated trunnion shaft, a rotary hollow dump grate supported in said shaft and having ports in the 45 portion of the shell thereof in contact with the combustible fuel, a valve carried by the trunnion for closing certain ports in the dump grate shell, and means for holding the valve in a predetermined position. 50

14. A dump grate for a stoker comprising a hollow cylinder having peripherally disposed ports, means for supplying fluid to the hollow cylinder, means for rotating the cylinder, a segmental cylindrical member 55 disposed within the hollow cylinder and arranged to close ports which in the rotation of the hollow cylinder are not in a position to discharge fluid into contact with the material supported by the hollow cylinder. 60

In testimony whereof, I have hereunto subscribed my name this twenty-fifth day of October, 1920.

JOSEPH G. WORKER.
